TIRE

Aristides Makris, Plainfield, N.J., assignor to The B. F. Goodrich Company, New York, N.Y., a corporation of New York

Filed Sept. 20, 1967, Ser. No. 8,670

Term of patent 14 years

(Cl. D90—20)

FIG. 1

FIG. 2

FIG. 1 is a fragmentary side elevational view of a tire showing my new design, it being understood that the portion shown is repeated throughout the circumference of the tire, the opposite side of the tire being substantially like the side shown; and

FIG. 2 is a partial section through the tire taken on the line 2—2 of FIG. 1.

The dominant features of my design reside in those portions shown in full lines.

I claim:

The ornamental design for a tire, substantially as shown and described.
